[57] CLAIM

The ornamental design for a wire support shelf, as shown and described.

DESCRIPTION

FIG. 1 is a bottom perspective view of a wire support shelf showing my new design, the shelf is shown broken away to indicate indeterminate length;

FIG. 2 is a reduced top plan view thereof;

FIG. 3 is a reduced bottom plan view thereof;

FIG. 4 is an enlarged side elevational view thereof;

FIG. 5 is an enlarged end elevational view thereof;

FIG. 6 is a bottom perspective view of a second embodiment of FIG. 1;

FIG. 7 is a reduced top plan view of FIG. 6;

FIG. 8 is a reduced bottom plan view of FIG. 6;

FIG. 9 is an enlarged side elevational view of FIG. 6;

FIG. 10 is an enlarged end elevational view of FIG. 6.
